UNITED STATES PATENT OFFICE.

WILBUR F. OSBORNE, OF ANSONIA, CONNECTICUT.

DESIGN FOR BUCKLE-PLATE.

Specification forming part of Design No. 7,347, dated March 31, 1874; application filed March 19, 1874.
[Term of Patent 3½ years.]

To all whom it may concern:

Be it known that I, WILBUR F. OSBORNE, of Ansonia, in the county of New Haven and State of Connecticut, have invented a new and original Design for Buckle Face-Plate; and I do hereby declare the following to be a full, clear, and exact description thereof, reference being had to the accompanying drawing, which shows a face view of my design.

This invention relates to the design of a dragon resting upon the face-plate of a buckle in such a manner that a unique and novel appearance is imparted to said plate, whereby it can be readily distinguished from buckle-plates heretofore made.

In the drawing, the letter A designates the

face-plate of a buckle, which may be of any selected shape or outline. On this plate is the figure B of a dragon, being a winged figure having a human bust and the curled tail of a sea-serpent or alligator. The head and shoulders of this figure are enveloped by a hood, appearing to be held in position by a chin-band, as shown.

What I claim as new, and desire to secure by Letters Patent, is—

The design herein shown of a dragon on the face-plate of a buckle, as set forth.

WILBUR F. OSBORNE.
